UNITED STATES PATENT OFFICE.

EDWARD M. BENTLEY, OF BROOKLYN, NEW YORK.

TELEPHONE-STATION APPARATUS.

SPECIFICATION forming part of Letters Patent No. 297,909, dated April 29, 1884.

Application filed January 10, 1884. (No model.)

To all whom it may concern:

Be it known that I, EDWARD M. BENTLEY, a citizen of the United States, residing at Brooklyn, New York, have invented certain new and useful Improvements in Telephone - Station Apparatus, of which the following is a specification.

My invention consists in devices whereby the telephonic apparatus is brought by a single movement into listening position, the same movement making all the necessary circuit-connections, and, if desired, also operating the signaling-generator.

The best form of my invention is illustrated in the accompanying drawings, wherein Figures 1 and 2 are respectively side and front elevations of the apparatus. Fig. 3 is a section on line xx of Fig. 2, and Fig. 4 is a detail.

In the drawings, L is an extensible lever-arm rigidly connected to an operating-shaft, p , which projects from the side of box N , in which it has its bearings. This arm carries at its outer extremity the receiving-telephone F , with its axis horizontal, and is made extensible by being constructed in two parts, o and k , the former part being forked and embracing the other part within the fork, so as to slide longitudinally thereon. The relative motion of the two parts is guided by pins s , projecting from part k into a slot in one branch of the fork of o , and they are normally held together by a spring, r . Any other method of longitudinal adjustment of the arm may be employed. The arm may also have a lateral movement on pivot m , being normally held straight by spring g . These movements allow the receiver to be brought to the ear of any one, and also permit a movement of the head for any purpose without removal of the instrument. Arm L is normally held up in the elevated position shown by a predominating spiral spring around shaft p , as shown in Fig. 3, though the spring may be replaced by a weight, or have any other desired form.

Fastened to shaft p , just inside the box, is a disk, H , of insulating material, which has three contact-springs, X , Z , and Q , projecting radially from it, and being firmly attached thereto. Two of these contact-springs are connected by curved strip I , and they all bear on

a circular series of metallic contact-plates, A , B , C , D , E . The distance of these plates is so adjusted that spring X , in its movement caused by depression of arm L , passes from A to B , and Q passes from C to E , while Z remains constantly on D . Another switch controlling the circuit is placed along lever-arm L , so that the operating-button b can be readily depressed by the thumb of any one grasping the lever-arm, to draw it down. This switch (shown in Fig. 4) consists of a spring, e , connected to the incoming line, and normally resting in contact with point a , but adapted to be pressed by button b from point a over 65 against point b .

It is obvious that, in place of the switch on the lever-arm, the ordinary connections for the calling-generator may be employed, the generator being in circuit with the call-bell, and a short-circuit around it being automatically broken by the rotation of the armature.

G is the call-bell. P S is the induction-coil. T is the transmitter, of the usual form, on the hinged door of the call-box. There is a toothed sector, k , on shaft p just inside of disk H , which gears into a pinion, f , on shaft M of the magneto-generator. The generator is not shown in full, its construction being well known; and the lines 5 and 6 represent the connection with the two commutator-brushes of the machine. The arm L is of such a length as to reach the ear of any one speaking into transmitter T . It normally rests, as shown, against stop R , in which case the circuit may be traced from 1 to spring e , contact a , bell G , plate A , spring X , strip I , spring Z , plate D , line 3, and out at 2. In this situation any incoming current will ring call-bell G , the transmitter and receiver being cut out.

It is obvious that L may be drawn down into listening position with or without depressing the button b , according as it is desired to work the generator to signal the central office or to listen or converse over the line. In the former case the circuit is from 1 to spring e , point d , line 6, generator, line 5, and out at 2. The generator being thus in circuit and its armature rotated by sector k , a signal will be sent over the line to the central office.

One or more swings of L may be made, and

line 4 and bell G may be included in the circuit. When the arm is drawn down without depression of button b, spring X passes from A to B, and Q from C to E. The circuit is then 5 from 1 to e, point a, receiver F, secondary S of induction-coil, plate B, spring X, strip I, spring Z, plate D, and out by lines 3 and 2. At the same time the local-battery circuit is closed from battery to transmitter T, primary 10 coil P, spring Q, plate E, to battery. In this case the parts are all in position for conversation. When through using, the arm L may be allowed to automatically return to its normal position by action of the coiled spring. If the 15 button b is depressed while the arm is being restored, a signal is sent to the central office, to indicate that the conversation is ended.

The advantages of my invention will be 20 readily appreciated. A single simple movement places the apparatus in position for conversation or signals the central office. It requires no time and is readily learned. The line is automatically restored to its normal position, and wear of the flexible cord usually 25 used is avoided.

I claim as my invention—

1. The combination of telephonic transmitter and receiver, one being fixed to a support and movable relatively to the other, a signaling-generator, and means for operating the 30 same, said means being actuated by the relative approach or recession of said transmitter and receiver to or from their adjacent operative position.

35 2. The combination of telephonic transmitter and receiver, one being fixed to a support and movable relatively to the other, a signaling-generator, means for operating the same, said means being actuated by the relative approach or recession of said transmitter and receiver to or from their adjacent operative position, and switching devices, also operated by 40 said movements of the telephone apparatus.

3. The combination of a telephone-support, 45 a telephonic receiver fixed thereto with electric connections, a signaling-generator, and mechanism driving said generator, and actuated by the movement of said support.

4. The combination of a lever-arm, a telephone supported thereby and fixed thereto, and a toothed sector on the axis of said lever-arm gearing into a pinion on the shaft of a 50 magneto-generator.

5. The combination of a telephone, a movable support attached thereto, a normally predominating retracting device for said support, a signaling-generator, and means for actuating 55 said generator by the movement of said support.

6. The combination of a lever-arm, a tele-

phone fixed thereto and supported thereby, a signaling-generator operated by said arm, and a sustaining-retractor for said arm, overcoming the weight of the telephone.

7. The combination of a call-bell and telephonic apparatus, a signaling-generator, an operating device for said generator to which the telephone-receiver is attached, and a switch actuated by said device for including the telephone apparatus in the main line. 65

8. The combination of a lever-arm, a receiving-telephone fixed thereto, a signaling-generator, and means for operating said generator by the movement of said arm.

9. The combination of a telephone-support, 75 a telephone carried thereby, electric conductors on said support, and an independently-operated switch also on said support, for changing the circuit formed by said conductors.

10. The combination of a telephone-support, 80 a telephone carried thereby, circuit-connections therefor, an electric generator, and a switch on said support, controlling the circuit of said generator.

11. The combination of a telephone call-box, 85 calling apparatus inclosed therein, a swinging door for the same, and a separately-inclosed transmitting-telephone on the said door.

12. The combination, with a transmitting-telephone, of an adjacent receiving-telephone, 90 a swinging supporting-arm therefor having freedom of vertical and lateral movement, and switching devices actuated by the movement of said arm, for including said telephone in the main line.

95 13. The combination, with a transmitting-telephone, of a receiving-telephone and a support therefor adapted to maintain it in a position for conversation adjacent to the transmitting-telephone, said receiving-telephone having also freedom of lateral movement relatively to the transmitting-telephone.

14. The combination of a lever-arm, a receiving-telephone fixed thereto, a signaling-generator, means for including said generator 105 in circuit without the telephone, and means for operating said generator by the movement of said arm.

15. The combination of a telephone fixed to a movable support, a generator actuated by the movement of said support, an induction-coil and local battery, and means for closing the circuit of said local battery by the movement of said support.

Signed this 10th day of January, A. D. 1884. 115

EDWARD M. BENTLEY.
